US00D829335S

(12) **United States Design Patent** (10) **Patent No.:** **US D829,335 S**
(45) **Date of Patent:** **** Sep. 25, 2018**

(54) **SKIN CARE DEVICE**

(71) Applicant: **Samsung Electronics Co., Ltd.**, Suwon-si (KR)

(72) Inventors: **Minsun Park**, Seoul (KR); **Moorim Kim**, Suwon-si (KR); **Jeonggun Lee**, Seoul (KR); **Shinhee Cho**, Suwon-si (KR); **Jinkyeong Kim**, Yongin-si (KR); **Seungjun Lee**, Yongin-si (KR)

(73) Assignee: **SAMSUNG ELECTRONICS CO., LTD.**, Suwon-si (KR)

(**) Term: **15 Years**

(21) Appl. No.: **29/596,288**

(22) Filed: **Mar. 7, 2017**

(30) **Foreign Application Priority Data**

Nov. 21, 2016 (KR) 30-2016-0055850

(51) LOC (11) Cl. **28-03**

(52) U.S. Cl.

USPC **D24/215**

(58) **Field of Classification Search**

USPC .... 601/2, 15, 19, 27-32, 46, 48, 52, 78, 79, 601/84-85, 93-94, 99, 112, 113, 114, 601/120, 121, 125, 129, 131, 134, 135, 601/DIG. 12, DIG. 14, DIG. 15, DIG. 16, 601/DIG. 17; D14/218; D24/200, 211, D24/212, 213, 214, 215; D30/160; D28/91.1; D9/726, 727, 729

CPC .. A61H 23/004; A61H 15/00; A61H 15/0092; A61H 2015/0014; A61H 7/00

See application file for complete search history.

(57) **CLAIM**

The ornamental design for a skin care device, as shown and described.

DESCRIPTION

FIG. 1 is a front perspective view of a skin care device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear perspective view thereof.

The dashed broken lines in the drawings represent portions of the skin care device that form no part of the claimed design.

1 Claim, 7 Drawing Sheets
